UNITED STATES PATENT OFFICE.

DAVID PATON, OF HALIFAX, ENGLAND, ASSIGNOR TO JOSEPH WILD & CO.,
OF NEW YORK, N. Y.

DESIGN FOR A CARPET-PATTERN.

Specification forming part of Design No. 6,008, dated July 23, 1872.

Specification describing a new and original Design for a Carpet, invented by DAVID PATON, of Halifax, in the county of York, England.

The accompanying photographic illustration fully represents my new design.

This invention relates to a new design for the borders of carpets and similar fabrics. The border consists of four longitudinal rows. The outermost row, which is on a dark background in the photograph, contains, alternately, small quatre-foils and three-pronged tufts

on an undulating support. The second row contains S scrolls with intervening beads. The third row is quite plain; while the fourth contains the main ornaments in shape of projecting foliated tufts of alternately varying appearance, as shown.

I claim as my invention—

The design for a carpet, as shown.

DAVID PATON.
